(57) **CLAIM**

I claim the ornamental design for a disposable paper cooking pot, as shown and described.

DESCRIPTION

FIG. 1 is a top plan view of a disposable paper cooking pot showing my new design in a flat configuration;
FIG. 2 is a perspective view thereof, illustrated in a folded configuration;

FIG. 3 is a top plan view of FIG. 2;

FIG. 4 is a bottom plan view of FIG. 2;

FIG. 5 is a rear elevational view of FIG. 2;

FIG. 6 is a left-side elevational view of FIG. 2, the right-side elevational view being a mirror image thereof; and,

FIG. 7 is a front elevational view of FIG. 2.

The broken lines showing a cover in FIG. 2 depict environmental matter and form no part of the claimed design. The remaining broken lines in FIG. 1 represent score lines.
